UNDERGARMENT

Frank A. Cohen, Brooklyn, N. Y.

Application July 23, 1943, Serial No. 495,812

9 Claims. (Cl. 2-28)

This invention relates to undergarments and, more particularly, to form constricting and molding undergarments such as corsets, girdles and the like.

The principal object of the invention is to provide a garment of the character described in which an improved control panel, such as is shown in my copending application for Form constricting and molding garments, Serial No. 495,811 filed July 23, 1943, is employed to mold the body symmetrically about an anchor line running centrally down the front of the wearer.

Another object of the invention is to provide a garment of the character described wherein such control panel affords a variation in resilience throughout its height corresponding to the variation in girth occasioned at different body levels upon movement of a wearer.

Other objects of the invention will in part be obvious and in part hereinafter pointed out.

The invention accordingly consists in the features of construction, combinations of elements and arrangements of parts which will be exemplified in the construction hereinafter described and of which the scope of application will be indicated in the appended claims.

In the accompanying drawing, in which there is shown one of the several possible embodiments of this invention,

Fig. 1 is a perspective view of a corset embodying my invention as it appears when worn, a portion thereof being broken away to illustrate the construction and location of the rear layer of the control panel;

Fig. 2 is a plan view of the inside of the corset, partly broken away to show the location of the outside layer of the control panel; and

Fig. 3 is an enlarged section taken substantially along the line 3-3 of Fig. 2.

In my aforesaid co-pending application, I have shown a control panel which comprises two superimposed layers of equal widths and shapes whose side edges are registered and attached to each other. One of the layers has a vertically extending area of flexible elastic material adjacent one side edge of the panel and the other layer has a vertically extending area of flexible elastic material adjacent the other side edge of the control panel. The remaining portion of each layer consists of a vertically extending area of flexible inelastic material. Thus each elastic area either overlies or underlies an inelastic area in the other layer so that when the control panel is stretched an inelastic area moves in a direction opposite to that in which the opposed elastic layer

moves and since the control panel is curved in use, this relative motion is opposed by frictional rubbing of the superimposed layers. As the layers are of equal width, this friction comes into immediate play to increase the control effected by the panel, lessen the strain imposed upon the elastic areas and afford maximum control for the quantity of elastic material employed. The elastic areas are also of equal width, and for this reason equally distribute the strain, create a maximum of friction, and obtain maximum stretch for given widths. The expression "of equal width" is used in a limited sense to connote equal widths at the same horizontal level.

Although a control panel of this construction may extend over substantially the entire front or rear of a garment, as shown and described in my said co-pending application, I have found that panels so disposed, although tending to provide a certain desirable control of the figure in profile, do not maintain symmetrical control about a line running centrally down the wearer's front. In accordance with the present invention, as will now be seen, I have incorporated my improved control panel in a garment in such manner that all the desirable functions thereof are retained and at the same time the garment will afford such symmetrical control.

Referring now in detail to the drawing, 10 denotes a corset embodying the present invention. Said corset comprises a back section 12 of conventional construction consisting, for example, of two panels 14, 16, each fabricated from a flexible inelastic material such as woven cloth which is stiffened by a plurality of vertically extending pocketed stays 18. The two back panels may be interconnected by a row of lacing 20, such as is usually employed in the art.

Two standard brassière sections 22, 24 may be secured to the upper side edges of each back panel 14, 16. The free edges of these sections are provided with hooks 26 and eyes 28 for detachably securing the sections to each other at the front of the body, and form, in conjunction with a top part of the back section 12, a body encircling bust supporting bandeau. Conventional shoulder straps may complete the upper part of the garment.

In accordance with the present invention, the lower front part of the garment 10 comprises two control panels 32, 34, each of which embodies the construction illustrated and described in my said co-pending application, i. e., each control panel 32, 34 comprises a front layer 36 and rear layer 38. The front layer includes a vertically extend-

ing area of flexible inelastic material such as plain woven cloth and consists of a plurality of strips 40, 42 of such material sewed to each other by a vertical line of stitching 44. Additionally, this inelastic area may include a vertically extending pocketed stay 46. Said front layer 36 also has a vertically extending strip 48 of elastic material as, for example sheet rubber, "lastex," or any woven or knitted fabric which includes strands of a resilient material like rubber. One side of this elastic strip forms an edge of the front layer 36.

The rear layer 38 likewise includes a vertically extending area of inelastic flexible material which comprises a strip 50 of cloth, and a vertically extending area of elastic material such as the strip 52 of "lastex." Both the elastic and inelastic areas of the rear layer 38 are mirror images of the elastic and inelastic areas of the superimposed front layer 36. One side of the elastic strip 52 in the rear layer also forms one of the edges of said layer.

The front and rear layers 36, 38 are of identical shapes and widths, the side edges being superimposed and attached to each other by vertical lines of stitching 54, 56. Said front and back layers are so arranged that the elastic strip 48 in the front layer overlies the inelastic strip 50 in the rear layer and the elastic strip 52 in the rear layer underlies the inelastic strip 40 in the front layer. In this fashion the elastic strips frictionally contact inelastic strips and relative movement thereof must be effected when the garment is forced to change its shape at such time as the body of a wearer moves.

The two control panels 32, 34 are of substantially similar construction and configuration so that they exert substantially similar degrees of figure control. Each control panel is connected at one side thereof to an edge of one of the back panels 14, 16 by a line of stitching 58. The other edge of each control panel is stitched to an edge of one of a pair of central panels 60 on whose opposite edges there are disposed a plurality of aligned attaching and detaching means, such as a lower series of hooks 62 and eyes 64 and an upper series of sockets 66 and headed studs 68. The strip of material to which these rapidly attachable and detachable means are connected is of inelastic material and defines a line extending vertically and centrally down the front of a wearer. This line is stiffened and reinforced against circumferential deflection by a pair of heavy metal strips 70 on which the sockets 66 and studs 68 are permanently and rigidly mounted. Said line serves as an anchor to both sides of which the control panels 32, 34 symmetrically control the figure and symmetrically yield to figure movement.

I have found that this construction effects an absolutely symmetrical molding of the figure about a line extending vertically and centrally down the front of the wearer, as distinguished from garments such as shown in my co-pending application which only control a figure in profile, and from garments employing single and double ply elastic control panels which, due to unsymmetrical yielding of the panels, can control neither in profile nor about the central line mentioned.

A feature of the invention resides in the particular shape of the elastic strips 48, 52, comprising the elastic areas of the front and back layers of a control panel. These strips are broad at the bottom and taper upward in a gradual and substantially uniform manner, to a pointed

apex if desired. Since the strips 48, 52 are mirror images of each other, as mentioned above, and since it is desirable to have the outer edge of the strip, which forms an edge of a control panel, extend almost vertically, the two strips appear to slant in opposite directions as clearly shown in Fig. 2. By tapering the strips in this manner I provide a substantial degree of resilience adjacent the bottom of the control panel and gradually and uniformly decrease the degree of resilience toward the top of said panel. This variation of resilience and thus of figure control, in proportion to the distance from the bottom of the garment is highly advantageous. Heretofore where a control panel of the type under consideration was employed the elastic areas were of substantially uniform width. Such a control panel, depending upon its size and resiliency, tended to exert either too strict a control in the region of the hips or too little in the region of the diaphragm. This was due to the fact that on the one hand frictional engagement between overlying elastic and inelastic panels was very hard to overcome if a narrow area of elastic was employed, and on the other hand frictional engagement did not exert a sufficient controlling influence if a wide area of elastic was employed. All the drawbacks of the previous constructions, however, have been avoided by tapering the elastic panels upwardly as described so that although the diaphragm increases in girth but slightly upon movement of the body, nevertheless, because the width of the resilient area is so slight in this region, the frictional effect is almost immediately felt. In contrast, by employing an undue width of elastic in the region of the hips the frictional restraint exerted by the panel does not appreciably affect the control afforded by the garment until a substantial change in the girth of the garment at such point is caused by movement of the wearer.

It will thus be seen that I have provided a garment in which the several objects of this invention are achieved and which is well adapted to meet the condition of practical use.

As various possible embodiments might be made of the above invention and as various changes might be made in the embodiment above set forth, it is to be understood that all matter herein described or shown in the accompanying drawing is to be interpreted as illustrative and not in a limiting sense.

Having thus described my invention, I claim as new and desire to secure by Letters Patent:

1. An undergarment of the character described comprising a back section and a front section, said front section including two control panels joined to each other vertically and centrally of the undergarment by a line of rapidly attachable and detachable fastening means, each of said panels comprising a front layer and a back layer, each of said layers including a vertically extending elastic area adjacent a different side edge of a panel, the two elastic areas in each control panel being of identical configuration and equal widths, the remaining portion of each layer including a vertically extending inelastic area whereby the elastic area in the front layer overlies the inelastic area in the back layer, and the elastic area in the back layer underlies the inelastic area in the front layer and friction opposes opposite movement of the layers when the panels are stretched in use.

2. An undergarment, as set forth in claim 1, wherein a side edge of each of the elastic areas

forms a side edge of the layer of which it is a part.

3. An undergarment, as set forth in claim 1, wherein a side edge of each of the elastic areas forms a side edge of the layer of which it is a part, wherein said layers are of identical configuration and width, and wherein the elastic areas in the front and back layers are mirror images of each other.

4. An undergarment, as set forth in claim 1, 10 wherein the layers in a panel are of identical width and the elastic areas in a panel are of identical width.

5. An undergarment, as set forth in claim 1, 15 wherein the elastic areas taper in width from the bottom edge of the garment upwardly.

6. An undergarment, as set forth in claim 1, wherein an anchor line is provided in the garment extending vertically and centrally down the front thereof along said fastening means.

7. An undergarment of the character described comprising a back section and a front section, said front section including two central panels joined to each other vertically and centrally of the undergarment by a line of rapidly attachable and detachable fastening means, a vertically extending metal strip in each of said central panels forming an anchor line running vertically and centrally down the front of the garment, and a control panel between each central panel and said back section, each control panel comprising a front layer and a back layer, said layers being of identical configuration and width and each including a vertically extending elastic area adjacent a different side edge of said control panel, 20 the remaining portion of each layer including a vertically extending inelastic area whereby the

elastic area in the front panel overlies the inelastic area in the back panel, and the elastic area in the back panel underlies the inelastic area in the front panel and friction opposes opposite movement of the layers when the control panels are stretched in use, the elastic areas of the front and back panels being mirror images of each other.

8. An undergarment, as set forth in claim 7, wherein at least a portion of said line of rapidly attachable and detachable fastening means are rigidly and permanently secured to the metal strips.

9. For use in a garment of the character described, a control panel which includes an outer layer and an inner layer superimposed on one another and of equal widths and shapes, the side edges of the layers being registered and attached to each other, one of said layers having a vertically extending area of flexible elastic material adjacent one side edge of the panel, and the other of said layers having a vertically extending area of flexible elastic material adjacent the other side edge of the panel, the remaining portions of each layer comprising a vertically extending area of flexible inelastic material which constitutes a major part of the layer whereby the elastic area in the outer layer overlies the inelastic area in the inner layer and the elastic area in the inner layer underlies the inelastic area in the outer layer and friction immediately opposes opposite movement of the curved superimposed contacting layers, said elastic areas being of equal widths and mirror images of each other, said elastic areas tapering in width from the bottom edge of the garment upwardly.

FRANK A. COHEN.
